UNITED STATES PATENT OFFICE

CHESTER L. DAVIS, OF KEOKUK, IOWA, ASSIGNOR TO WIRED RADIO, INC., OF NEW YORK, N. Y., A CORPORATION OF DELAWARE

TELEVISION SYSTEM

Application filed June 28, 1930. Serial No. 464,643.

My invention relates broadly to television systems and more particularly to a method and apparatus for the reproduction of images in a television system.

5 One of the objects of my invention is to provide means for rendering visible an image at a television receiver.

Another object of my invention is to provide an arrangement of image reproducing means for a receiver in a television signaling system wherein a potential node is caused to move along a screen for the reflection of light to an observing position.

A further object of my invention is to provide a construction of luminously responsive screen and observing means therefor in a television receiving circuit.

A still further object of my invention is to provide an arrangement of inductive electrical screen along which a potential node is caused to move in accordance with signaling energy transmitted from a distant point for forming an image which is rendered visible adjacent one side of a cabinet structure.

25 Other and further objects of my invention reside in the arrangement of circuits for a television signaling system as set forth more fully in the specification hereinafter following by reference to the accompanying drawings, wherein:

Figure 1 is a theoretical view illustrating the optical arrangement of the television screen at a receiver and the arrangement of image observing means adjacent thereto; Fig. 2 illustrates a vertical cross-sectional view of the image reproducing screen of my invention; Fig. 3 illustrates a cross-sectional view of the image reproducing screen; Fig. 4 diagrammatically shows the arrangement of potential in a television transmission system embodying the principles of my invention; Fig. 5 shows a circuit arrangement for a television receiver embodying the principles of my invention; Fig. 6 illustrates one embodiment of image reproducing means constituting my invention; and Fig. 7 illustrates a modified form of image reproducing means embodying my invention.

The television system of my invention makes use of the principles which have been

set forth in detail in my Letters Patent No. 1,756,086, dated April 29, 1930, entitled "Signaling system", and shown in my applications Serial No. 299,501, filed August 14, 1928, entitled "Glow discharge device", now Patent No. 1,789,219, dated Jan. 13, 1930, and application Serial No. 414,957, filed December 18, 1929, entitled "Television system". For a further understanding of the television system of my invention reference is made to my copending application Serial No. 460,760, filed June 12, 1930, entitled "Television system".

In the television system of my present invention, I arrange an inductive screen indicated at 1 in a position subject to the illumination of light rays from the illuminating means 2. The light rays from screen 1 pass through lens 3 and are directed upon the screen 4. A potential node moving along the inductive screen 1 is reproduced as an image on screen 4 due to the reflection of light from the illuminating means 2. The inductive screen comprises an inductance having a multiplicity of turns extending in parallel alignment one with respect to another and disposed in the same plane as represented in Figs. 2 and 3. The inductive screen is positioned adjacent the reflector 8 located either within the glass envelope 5 or exteriorly thereof. The reflector 8 has a silvered or polished surface and serves to reflect the movement of a potential node along the inductance. The reflector may extend outside the rear wall of the envelope 5 or it may be disposed inside the rear wall thereof. The movement of the potential node along the inductance is produced by a transmission system having a periodically varying frequency characteristic produced by a transmission circuit involving the principle illustrated in Fig. 4. In this diagram the antenna-ground circuit is designated at 28-29 connected to the tuned circuit 30-37. A power amplifier 31 connects to the radiating circuit and the oscillator 32 connects to the power amplifier circuit. A modulation circuit for the oscillator is shown at 33 to which photoelectric cell 34 is connected. Driving motor 36 operating scanning disc 35 is operated to move the scanning disc in timed rela-

tion to a recurring change in frequency of the transmitted energy by means of the connecting link designated at 41. The object 38 is illuminated from the source 39 and reflects 5 light through the scanning disc 35 upon the photoelectric cell 34 for varying the resistance thereof.

At the receiver a circuit arrangement as 10 illustrated in Fig. 5 is employed including an antenna-ground designated at 10—11 connected to a coupling circuit illustrated at 12 to which there is connected the radio frequency 15 amplifier stage 14, the detector 16 and the oscillator 17. The detector 16 is coupled to the output of the radio frequency amplifier 14 through transformer circuit 15. The circuits of the radio frequency amplifier stage 14 and detector 16 are tuned as designated at 19 and 20 respectively. The oscillator includes 20 variable condenser 18 connected in circuit with the inductive screen 1 and the oscillatory circuit 22. The inductive screen 1 has terminals 6 and 7 connecting the circuit of the oscillator 17. The driving motor 21 operates 25 in synchronism with the motor 36 at the transmitter and periodically varies the capacity of condenser 18 and condensers 19 and 20 in the receiver through a suitable mechanical interlinkage designated at 24. The 30 period of the screen 1 is therefore made to sweep a recurring frequency band and the potential node is shifted along the screen in accordance with the incoming signaling energy. The light emanating from source 2 35 illuminates the potential node which shifts along the inductive screen 1. The movement of the node is reproduced on screen 4 through the lens 3. In order that the image may be more clearly reproduced, I enclose the envelope 5 which contains the inductive screen 1 within a cabinet structure designated at 25 and within which the screen is subjected to light rays from the source 2, the light being directed through optical system 3 upon the 40 screen 4. By selecting suitable color contrast between the illuminating means 2 and the gas content in the glow discharge tube constituting the inductive screen 1, the desired 45 intensity of reflection may be obtained upon the screen 4. The receiver has been diagrammatically illustrated in Fig. 6 as having the 50 output of the oscillator connected to the inductive screen 1.

In Fig. 7, I have shown the inductive screen 55 1 disposed within a cabinet structure 5 but with the reflecting surface 8 removed from the glow discharge tube 1. A light source 40 disposed adjacent a reflector 27 is positioned at a predetermined distance behind the 60 inductive screen 1 in order that light rays of suitable color contrast to the luminous discharge of the inductive screen 1 may be directed through optical system 3 for reproduction as an image upon screen 4. The 65 source of illumination 40 is selected of such

color characteristic in contrast with the luminous discharge tube 1 as will permit display of the movable node along screen 4 to the best possible advantage. In the arrangement illustrated in Fig. 7, the reflector 8 is omitted from the luminous discharge device. The receiver in Fig. 7 has been illustrated diagrammatically in a manner similar to the arrangement shown in Fig. 6 with the luminous discharge tube 1 in the output of the oscillator 75 circuit.

The successive movement of potential nodes of different intensity due to the transmitter control produces luminous glow in the glow discharge tube 1 having different light reflective or filter properties enabling the image to be reproduced in desired proportions upon the screen 4.

For the purposes of illustrating my invention, I have shown the television system in 80 connection with space radio circuits but it will be understood that the principles of my invention are equally applicable to wired radio systems.

While I have described my invention in 90 certain preferred embodiments, I desire that it be understood that modifications may be made and that no limitations upon my invention are intended other than are imposed by the scope of the appended claims.

What I claim as new and desire to secure by Letters Patent of the United States is as follows:

1. In a television system, means for receiving electrical energy over a recurring band of 100 frequencies, a cabinet structure, an inductive screen disposed within said cabinet structure and luminously responsive to potential variations in the received signaling energy, means mounted in said cabinet structure out of the field of view of said inductive screen for directing light upon said surface, an image reproducing screen, and an optical system centrally aligned with respect to said cabinet structure and interposed between said inductive screen and said image reproducing surface for visually reproducing the movement of potential nodes along said inductive screen.

2. In a television system, a receiving circuit responsive to signaling energy over a 115 variable range of frequencies, an enclosing casing, a luminously responsive screen for reproducing the movement of potential node in accordance with the characteristic of the transmitted energy disposed interiorly of said casing adjacent one end thereof, an image reproducing surface, an optical system carried by said casing and interposed between said luminously responsive surface and said image reproducing screen, and means disposed in the other end of said casing out of the field of view of said optical system for illuminating said luminously responsive screen 120 for reflecting the movement of a potential 125 node along said screen.

node thereon upon said image reproducing surface.

3. In a television system, a circuit for receiving television signaling energy, a cabinet structure opaque to light, a glow discharge tube responsive to variations in intensity of the receiving signaling energy and mounted interiorly of said cabinet structure adjacent one end thereof, an image reproducing surface, an optical system disposed centrally in the other end of said cabinet structure and interposed between said glow discharge tube and said image reproducing surface, and means disposed within said cabinet structure adjacent the end thereof which carries said optical system for illuminating said glow discharge tube for reflecting variations in light intensity upon said image reproducing surface.
- 10 4. A television system comprising a circuit responsive to television signaling energy, a cabinet opaque to light, a luminously responsive screen extending parallel to the rear wall of said cabinet and subject to variations in glow according to variations in potential of the received signaling energy, an image reproducing surface exterior to said cabinet, an optical system carried by the front wall of said cabinet centrally of said screen and interposed between said image reproducing surface and said luminously responsive screen, and means within said cabinet adjacent the front wall thereof and located out of the field of view of said optical system for directing 25 light rays upon said luminously responsive screen for reproducing an image through said optical system upon said image reproducing surface.
